UNITED STATES PATENT OFFICE.

RAY SIMPSON, OF RIVER FOREST, ILLINOIS, ASSIGNOR TO JEWELL ELECTRICAL INSTRUMENT CO., OF CHICAGO, ILLINOIS, A CORPORATION OF ILLINOIS.

SPOOL FOR ELECTRICAL INSTRUMENTS AND THE LIKE.

Application filed July 18, 1927. Serial No. 206,434.

The present invention relates to spools for electrical instruments and the like and a method of constructing electrical connectors for such spools and other small electrical parts.

One of the objects of my invention is the provision of a spool for electrical instruments having a conducting member molded into and secured in said spool at a plurality of points in such manner that the conductor may be severed between any of its points of support and bent to form a simple connector.

Another object of my invention is the provision of a novel form of construction for small electrical parts and connectors of the class described, upon which all projecting parts are circular in cross section so that dies may be constructed with a minimum of labor upon a lathe.

Another object of my invention is the provision of a novel method of constructing or forming the spools and connectors of the class described.

Other objects and advantages of my invention will appear more fully from the following description and from the accompanying drawings, in which similar characters of reference indicate similar parts throughout the several views.

In the drawings:

Fig. 1 is a plan view of a spool at one of the stages in the formation of the connectors;

Fig. 2 is an elevational cross sectional view on the lines 2—2 of Fig. 1;

Fig. 3 is a plan view of the finished spool and connectors; and

Fig. 4 is a side elevational view of the same.

Referring to Figs. 1 and 2, 10 indicates in its entirety my spool and its associated parts in this stage of its manufacture. The spool 10 is preferably formed with a rod or shaft 11 supporting at each end a disc or flange 12 and 13 projecting at substantially right-angles to the shaft 11.

The shaft 11 and the flanges 12 and 13 are preferably, but not necessarily, formed with an axial bore 14 for convenience in attachment of the spool to other parts and for use in winding the spool; however, the spool may also be formed without such a bore.

The spool 10 is provided at one or both of its ends with a plurality of projecting bosses 15, 16, 17 and 18, and the bosses 15 to 18 are preferably made of substantially circular

cross section in order to facilitate the manufacture of dies. The dies may thus be made upon a lathe with a minimum of labor and machining. The bosses are also preferably slightly tapered to facilitate the molding operation.

In order to provide a simple, efficient and inexpensive connector for spools of the class described, I prefer to mold the spool 10 of bakelite or other insulating compound and during this molding operation there may be imbedded in the bosses 15 to 18 an electrical conductor 19.

The conductor 19 is preferably located within the bosses upon the exterior surface 70 of the flange 13 but, if desired, it may be spaced slightly from said surface without dispensing with many of the advantages of the invention. The conductor 19 is preferably a strip of thin sheet metal of electrical 75 conducting qualities, such as copper, and it is preferably in the form of an annular ring, as shown in Fig. 1.

The flange 13 may also be formed with a plurality of small apertures 20 located near 80 its outer edge for the passage of the electrical conductors which form the coils 21. The flange 13 may also be provided with similar apertures 22 near the shaft 11 to permit the passage of the inner end of one or more conductors forming the coils 21.

After the spool has been molded as shown in Figs. 1 and 2, with the conductor 19 imbedded at a plurality of points, such as the bosses 15 to 18, this spool may be employed 90 for supporting any number of separate coils for electrical instruments or other purposes. A number of separate connectors may then be formed, depending upon the number of coils employed upon the spool, and the method of forming these connectors is as follows: A saw or other cutting instrument capable of severing the conductor 19 may be used and the conductor 19 cut at a plurality of points such as 23, 24, 25 and 26. This effectively 100 separates the conductor 19 into a plurality of short segments, each of which is supported by one or more bosses in which the segment is imbedded, and I desire to be understood that any number of such bosses and cuts may 105 be employed.

The loose ends 27, 28, 29 and 30 of the segments may then be bent upward and back upon themselves, as shown in Figs. 3 and 4, to form a plurality of connectors 31, to which 110

terminals may be soldered or otherwise permanently connected. The spool 10 may then be wound with a plurality of turns of insulated wire or spaced turns of wire separated by insulating layers, thereby forming the coils 21. The ends of the coils may be brought up through the apertures 20 or 22 and soldered or otherwise permanently connected to any of the segments of the conductor 19.

As shown in Fig. 3, both the terminal wires 32 and the ends 33 of the coils have been inserted within a single connector 31 and secured by soldering.

15 Another method of accomplishing the same result is to solder the end 33 of the coil to the segment at another point, reserving the connector 31 for the terminal 32.

If desired, the cuts 24 may be made midway 20 between a pair of bosses so that two loose ends or segments will be available on each side of the boss. One of these ends may be used as a connector for the end 33 of a coil, while the other end of the segment may be used as a 25 connector for a terminal 32.

It will thus be observed that I have provided a simple and economical structure by which any number of connectors may be formed upon a spool of uniform type and 30 that my spool is adapted to be molded of bakelite or other insulating compound with the connectors secured therein at a plurality of points. The dies for molding such parts may be constructed with a minimum of labor 35 because all of the parts are circular in cross section and the spool and connector thereby provided are durable, economical and efficient.

While I have described my novel connector and its form of support as applied to an insulating spool for electrical instruments, I 40 desire to be understood that my invention is not necessarily confined to use upon spools but may be employed upon small electrical parts of all kinds, wherever it is desired to 45 use connectors of the type described, such as upon transformer casings or casings for other small electrical parts.

While I have illustrated and described a preferred embodiment of my invention, many 50 modifications may be made without departing from the spirit of the invention, and I do not wish to be limited to the precise details set forth but desire to avail myself of all changes within the scope of the appended claims.

55 Having thus described my invention, what I claim as new and desire to secure by Letters Patent of the United States is:

1. In an electrical instrument, a spool for coils or the like, comprising a molded insulating member having a plurality of cylindrical

bosses molded thereon and a conductor supported on said spool by molding the same in one or more of said bosses.

2. In an electrical apparatus, a molded insulating member having ends of circular cross section and having a boss of circular cross section molded on said member, and a strip of electrical conducting material molded in said boss and exposed at other points on said member to form an electrical connector. 70

3. In an electrical apparatus, a molded insulating member having ends of circular cross section and having a plurality of bosses of circular cross section molded on said member, and a ring of electrical conducting material 75 molded in said bosses on the surface of said member.

4. The method of forming an electrical connector, comprising molding an insulating support with a strip of electrical conducting 80 material molded therein at a plurality of points and exposed at other points and severing the strip between one or more points of support.

5. The method of forming an electrical connector, comprising molding an insulating support with a strip of electrical conducting material molded therein at a plurality of points and exposed at other points, severing 85 the strip between one or more points of support and bending said strip to form an electrical connector. 90

6. In a new article of manufacture, a coil unit for electrical instruments and the like comprising a molded insulating spool having 95 a plurality of integral frustro-conical bosses carried by one end, and a ring of electrical conducting material lying on one end of said spool and secured by molding in said bosses, said ring being severed between certain of 100 said bosses, and bent to form electrical connectors.

7. In a new article of manufacture, a coil unit for electrical instruments and the like comprising a molded insulating spool having 105 a plurality of integral frustro-conical bosses carried by one end, a ring of electrical conducting material lying on one end of said spool and secured by molding in said bosses, said ring being severed between certain of 110 said bosses, and bent to form electrical connectors, and a plurality of turns of electrical conductor wound upon said spool, the ends of said turns of electrical conductor passing through the ends of said spool and being secured to said connectors. 115

In witness whereof, I hereunto subscribe my name this 12th day of July, 1927.

RAY SIMPSON.
